United States Patent Office

Des. 192,181
Patented Feb. 6, 1962

192,181

SURFACE FINISH GAUGE

Cyrus B. Kurtz, 3372 Mayfield Road, Cleveland, Ohio

Filed June 15, 1959, Ser. No. 56,337

Term of patent 7 years

(Cl. D52—6)

FIG. 1

FIG. 2

FIG. 3

FIGURE 1 is a side perspective view of a surface finish gauge showing my new design;

FIGURE 2 is a side elevational view thereof; and

FIGURE 3 is an end elevational view thereof.

I claim:

The ornamental design for a surface finish gauge, as shown.
